John Lane New Haven Connecticut
Design for sewing Butterfly

Wes. 610

John Lane, of New Haven, Conn.
Letters Patent No. 610. - Dated Nov. 8th, 1853.

The schedule referred to in these Letters Patent, and making part of the same.

To all whom it may concern:

Be it known that I, John Lane of the City, Town, and County of New Haven, in the State of Connecticut, have invented or produced a new and original design for an instrument for holding Ladies' sewing work, called a sewing butterfly, and I do hereby declare that the following is a full and exact description of the same, reference being had to the drawings hereto annexed, in which

Figure 1 is a view of the instrument complete, and

Figure 2 is a view of the top of the butterfly.

The part represented in the drawing, and designated by the letters a a a is a holder by which the instrument may be placed upon the side of a bench or table, and securely fastened by the screw b. The upper and lower parts c c of the body of the butterfly are attached to each other by the hinge d moving freely upon the hinge, and are at the same time acted upon by the spring e, thus forming a clasp nipping tightly at the head of the butterfly for the purpose of holding sewing work inserted therein.

The instrument when complete thus represents a butterfly with wings spread, as shown in the drawing.

Attached to the holder is an emery or cushion f, made in the form of a flower, as shown in the drawings.

What I claim as my invention and desire to secure by Letters Patent, is the device or design of a butterfly bending over a flower, when adapted and arranged for an instrument for holding sewing or other like work, as shown in the drawings.

Witnesses,

Isaac H. Bromley, }
Lucius G. Peck.

John Lane.
